UNITED STATES PATENT OFFICE.

CHARLES DE B. SHEPARD, OF NEW YORK, N. Y.

CENTRIFUGAL LIQUID-SEPARATOR.

SPECIFICATION forming part of Letters Patent No. 375,012, dated December 20, 1887.

Application filed April 29, 1887. Serial No. 236,584. (No model.)

To all whom it may concern:

Be it known that I, CHARLES DE B. SHEPARD, a citizen of the United States, residing at New York, in the county of New York, 5 State of New York, have invented certain new and useful Improvements in Centrifugal Liquid-Separators, of which the following is a specification, reference being had therein to the accompanying drawings.

10 This invention has relation to a discharge-conductor for centrifugal liquid-separators.

The object of the invention is to provide a conductor which can be cheaply manufactured and rendered capable of long service by a renewal of that portion thereof that is subjected to the greatest wear, and which can be readily adjusted, for purposes hereinafter specified, and which can furthermore be employed as a conductor for delivering a liquid from a 20 centrifugal machine to a point above said machine, all as hereinafter described.

Other objects and advantages of the invention will hereinafter appear, and the novel features thereof will be particularly pointed 25 out in the claims.

Referring to the drawings, Figure 1 is a side elevation of my conductor as applied to a centrifugal machine, the bowl of which is partially shown in a substantially central vertical 30 section. Fig. 2 is a central longitudinal vertical section of my conductor. Figs. 3 and 4 are views of modifications, and Fig. 5 is a perspective of my removable tip for a conductor.

Like letters of reference indicate like parts 35 in all the figures of the drawings.

A represents the bowl of a centrifugal machine, and in this instance it is provided with a depending neck, A', having a cream-discharge port, A², and an upper annular chamber, A³, through the bottom of which there extends a pipe, A⁴, directly to and in contact with the inner wall of the bowl, to which it is secured by solder, brazing, or any other suitable manner, as shown at A⁵. It is understood, also, that the upper end of the pipe A⁴ is rigidly secured in the bottom of the annular chamber A³. By this construction the heavier constituent of the liquid being separated is conducted by the pipe A⁴ upwardly into the 45 annular chamber A³, and the bowl itself is

strengthened against expansion by the centrifugal force generated during the operation of the bowl.

By the described connection of the pipe A⁴ a much stronger construction is secured than 55 any which involves the passage of the pipe through the side wall of the annular chamber.

It is understood that a suitable cream-receptacle will be provided beneath the bowl for the reception of that constituent of milk when the 60 same is being subdivided into its constituent elements.

Although I have mentioned the application of my invention to the separation of milk from cream, it is understood that the same may be 65 used for any other purpose to which it is adapted and for the separation of any other liquids than milk.

B represents any suitable fixed part of the frame-work of a centrifugal machine, and it 70 projects over the bowl and terminates centrally therewith in a sleeve, B', which is secured in any suitable manner to the bracket B. A set-screw, B², is threaded in the sleeve for the purpose of retaining my discharge-conductor in a desired position, as hereinafter 75 described.

C represents my conductor, or rather the body portion thereof, and it consists of a tube of any desired configuration in cross-section. 80 At one end of the tube there is removably inserted a tip, D, which is at one end rectangular in cross-section, thereby providing four sides, D', which in operation serve as cutting-edges. The tip is also provided with an annular rib or flange, D², which serves to prevent a liquid from creeping up and along the discharge-conductor. The remaining portion of the tip is in this instance cylindrical and screw-threaded, as at D³, so as to be connected 90 with the conductor C, which is interiorly screw-threaded, as at C'.

I do not limit my invention in this regard to a screw-threaded connection of the tip with the conductor; but I may substitute therefor 95 any other form of connection which will suggest itself to persons skilled in the art of constructing conductors generally.

The body portion of the conductor is provided with as many slots or grooves C² as 100

there are sides or cutting-edges D' on the tip. In this instance four cutting-edges or sides are formed on the tip by giving it a rectangular contour in cross-section; but it is evident that any polygonal contour would present a series of cutting-edges. I therefore in such cases provide as many grooves C² as there are sides to the tip. The grooves may be sunken in the body of the tube, as shown in Fig. 2; or an annular rib, boss, or collar may be formed on the tube, and the grooves C² may extend longitudinally therethrough, as shown in Fig. 4, in which case a lug, B³, for entering a groove may be formed on the sleeve B', so that the set-screw B² may be so arranged as to bear upon the shoulder or tube at points between the grooves. In the construction shown in Figs. 1 and 2 the set-screw projects into the groove C², and thus acts to prevent, as does the lug B³, Fig. 4, any rotation of the conductor within the sleeve, while at the same time it has freedom of movement longitudinally therein.

As thus far described the longitudinal adjustment of the conductor is intended to be produced directly by hand, and for all practical purposes this is sufficient; but in some instances an exceedingly fine adjustment of the longitudinal movement of the conductor may be required, and in such instances I form in the sleeve B', and at one end thereof, an annular groove, B⁴, into which the latch or lug E', secured to a hand-wheel, E, by a bolt, E², takes. The hand-wheel is interiorly screw-threaded, as at E³, to fit an exterior thread, C³, formed on the conductor. In this construction the rotation of the hand-wheel will cause the conductor to travel longitudinally in the sleeve, while the set-nut B² or a lug, B³, in the groove C² of the conductor will prevent any rotation of the conductor within the tube. The opposite end of the tube is provided with an elbow, F, which may be rotated, so as to be presented in different directions for the delivery of the liquid through the conductor to different desired points. In this instance the rotation of the elbow F is provided for by means of a screw-collar, F', threaded or otherwise secured to the conductor C, and 50 a cap, F², threaded to the collar, the cap being adapted to permit of the introduction therein of the elbow and its flange F³, so that the whole may be secured in a liquid-tight manner in connection with the conductor. A hose, 55 F⁴, may be applied to the elbow and serve to conduct the constituents being delivered from the machine to a point above the same.

In the operation of a centrifugal machine the constituent elements are, when delivered by a conductor of this class, thrown with comparatively great force, so that by providing a connection with the discharge-conductor which is capable of being disposed to deliver in all directions I utilize the machine in such 65 a manner as to cause it to take the place and

perform the function of a pump. In many cheese-factories the milk is creamed for the purpose of the manufacture of butter, and it is then necessary to pump the skimmed milk to an upper floor of the factory. By my construction, as before stated, I have avoided the necessity, expense, and cost of running a pump.

It is known that when a machine of this character is in operation the body of skimmed milk within the bowl is by centrifugal force rendered exceedingly firm and capable of offering the resistance of a solid body, so that conductors of this class invariably wear away with great rapidity at the point which comes into contact with the liquid. Now, by providing a removable tip I avoid the necessity of a provision of an entirely new conductor the tip of which has become worn. Furthermore, by giving my tip a polygonal form and 80 providing a slot or groove in the body of the conductor relatively arranged with the sides of the tip and permitting only longitudinal movement of the conductor in any adjustment thereof, I am enabled to present a desired cutting-edge or side to the liquid, and to change from one side to another of the tip, still preserving a proper presentation of the side or cutting-edge.

There is a material advantage accompanying 95 a conductor which has only longitudinal movement in its supporting-sleeve, in that it can be instantaneously withdrawn from the bowl, while in the use of a screw-threaded conductor more time is required to change the relative 100 position of the same with regard to the bowl.

Having thus fully described my invention and its operation, what I claim is—

1. A discharge-conductor for centrifugal liquid-separators, consisting of a pipe having 105 a polygonal tip and grooved in line with the several faces of the tip, whereby the same may be adjusted to expose either face of the tip to action, substantially as specified.

2. A discharge-conductor for centrifugal liquid-separators, provided with grooves, in combination with a bracket for supporting the same, provided with a set-screw adapted to fit the grooves, substantially as specified.

3. The separating-bowl having an upper annular chamber and a pipe extending from the inner surface of the bowl, to which it is firmly attached, to the top of the bowl, so as to communicate with said annular chamber, and having a depending neck provided with a port for the lighter constituent, in combination with the discharge-conductor provided with grooves or their described equivalents, and a device for adjustably securing the conductor in the desired position, substantially as specified. 115 120 125

4. The bowl A, having the annular chamber A³, and provided with the pipe A⁴, passing through the bottom of the annular chamber to the wall of the bowl and firmly secured 130

at each end to the wall and to the bottom of the chamber, respectively, substantially as specified.

5. The removable tip D, polygonal in cross-section at one end, each of its sides formed as a cutting-edge, and provided with an annular rib and at the other end with a screw-threaded shank, substantially as specified.

In testimony whereof I affix my signature in presence of two witnesses.

CHARLES DE B. SHEPARD.
